[57] **CLAIM**

The ornamental design for a flower pot cover, as shown and described.

DESCRIPTION

FIG. 1 is a perspective view of our new flower pot cover design;

FIG. 2 is a reduced side elevational view thereof;

FIG. 3 is a reduced top plan view thereof;

FIG. 4 is a reduced bottom plan view thereof;

FIG. 5 is a side elevational view of a second embodiment of our new design;

FIG. 6 is a side elevational view of a third embodiment of our new design;

FIG. 7 is a side elevational view of a fourth embodiment off our new design; and,

FIG. 8 is a side elevational view of a fifth embodiment of our new design.

The flower pot cover has no substantial thickness.
